UNITED STATES PATENT OFFICE.

WILLIAM N. KIMBALL, OF BRADFORD, AND WALTER H. HERSEY, OF HAVERHILL, MASSACHUSETTS.

SPINNING-MULE.

SPECIFICATION forming part of Letters Patent No. 388,054, dated August 21, 1888.

Application filed April 13, 1887. Serial No. 234,704. (No model.)

To all whom it may concern:

Be it known that we, WILLIAM N. KIMBALL, of Bradford, and WALTER H. HERSEY, of Haverhill, citizens of the United States, both 5 in the county of Essex and State of Massachusetts, have invented a new and useful Improvement in Spinning-Mules, of which the following is a specification.

In certain grades of work in spinning yarns 10 it becomes necessary to twist the warp one way and the filling-yarn in the reverse direction in order to obtain the best results in the appearance of the cloth. In the present method of doing this it becomes necessary to change 15 each spindle-band, and, as there are from three to five hundred spindles to a mule, the time employed in changing the bands, which necessitates the stoppage of the mules, renders it a tedious and expensive operation.

20 The object of our invention is to enable the spindles to rotate in either direction as required without the necessity of changing the spindle-bands, thereby effecting a great saving of time and labor, as well as wear and tear 25 of the bands.

Our invention is illustrated in the accompanying drawings, in which—

Figure 1 is a top or plan view of the main shaft of a mule-carriage and mechanism embodying our invention for rotating the spindles 30 in either direction. Fig. 2 is a horizontal section through the same. Fig. 3 is a transverse vertical section through a mule and carriage, showing our device applied to the mule-carriage.

35 *a* is the main shaft provided at each end with the couplings *u* *v*, that carry the band-cylinder. On the main shaft *a* is fitted a sleeve, *s*, carrying the faller mechanism *d* *e* *f*, the 40 winding-gear *c*, and clutches *b* *b*. On the shaft *a* is also mounted the gear *m*, and a gear, *p*, is mounted upon the sleeve *s*.

Inside the mule-carriage is mounted an additional shaft, *h*, which carries the rim-pulley 45 *g* and cog-wheel *k*, which are both fast on the shaft *h*, and also a cog-wheel, *i*, which is held by a feather and groove on the shaft, so that it is free to be moved in and out of gear with the cog-wheel *m* on shaft *a*, and when in the 50 desired position it is secured by a set-screw, *i*. The cog-wheel *k* on shaft *h* is always in com-

munication with the cog-wheel *p* on sleeve *s* through the intermediate gear, *o*. When the shafts *a* and *h* are to rotate in the same direction, the gears *k* *o* *p*, being in connection, transmit motion from shaft *h* to sleeve *s*, and the sleeve is secured to the shaft *a* by means of a pin, *t*, passing through the sleeve and the shaft. When this is the case, the gear *i* on shaft *h* is moved along said shaft out of connection with the gear *m*, as shown in Fig. 1.

When the shafts *a* and *h* are to be rotated in opposite directions, the pin *t* is drawn out from the sleeve *s* and shaft *a*, which allows the sleeve to turn loosely on the shaft, and the gear *i* is moved on shaft *h*, so as to be in connection with the gear *m*, as shown in Fig. 2, so that the sleeve *s* is rotated in one direction, while the shaft *a* is rotated in the opposite direction.

70 The spindles *X* (see Fig. 3) are driven by means of bands *y* passing over the cylinders *z*, connected with the couplings *u* and *v*, and motion is imparted to the shaft *h* by the band *q* passing over the rim-pulley *g* in the ordinary manner.

75 By the means above described it will be seen that the shaft *a* may be driven in the same or in the opposite direction to the shaft *h*, as required, and the necessity of changing the spindle-bands for reversing the motion of the spindles is dispensed with.

What we claim as our invention is—

1. The shaft *a*, provided with the gear *m*, in combination with the shaft *h*, provided with 80 the adjustable gear *i* and gear *k*, the intermediate gear, *o*, gear *p*, the sleeve *s*, and pin *t*, substantially as shown and described.

2. The sleeve *s*, provided with gear *p*, in combination with the shaft *a*, provided with 85 gear *m*, the pin *t*, the shaft *h*, provided with gear *i*, band-pulley *g*, and gear *k*, and the intermediate gear, *o*, substantially as and for the purposes set forth.

In testimony whereof we have signed our 90 names to this specification in the presence of two subscribing witnesses.

WILLIAM N. KIMBALL.
WALTER H. HERSEY.
